UNITED STATES PATENT OFFICE.

LOUIS J. STOLL AND ERNEST JOHNSON, OF LINCOLN, NEBRASKA; SAID STOLL AS SIGNOR TO SAID JOHNSON.

CYLINDER-TOOTH WRENCH.

Application filed February 3, 1923. Serial No. 616,706.

To all whom it may concern:

Be it known that we, LOUIS J. STOLL and ERNEST JOHNSON, citizens of the United States, residing at Lincoln, in the county 5 of Lancaster and State of Nebraska, have invented certain new and useful Improvements in Cylinder-Tooth Wrenches, of which the following is a specification.

This invention relates to an improved 10 cylinder tooth wrench and seeks, as one of its principal objects, to provide a wrench which may be readily slipped between the bars of a threshing machine cylinder to engage the nuts upon the inner ends of the 15 cylinder teeth and operated for tightening said nuts.

The invention has as a further object 20 to provide a wrench embodying means to accommodate a bar or the like which may be employed as a lever for turning the wrench.

And the invention has as a still further 25 object to provide a wrench embodying means for straightening cylinder teeth.

Other and incidental objects will appear hereinafter.

In the drawings:

Figure 1 is a plan view showing our improved wrench in use.

Figure 2 is a perspective view of the wrench.

Figure 3 is a detail elevation showing the manner in which the wrench is used for straightening a cylinder tooth, and

Figure 4 is a detail sectional view on the line 4—4 of Figure 3, looking in the direction of the arrows.

Referring now more particularly to the drawings, it will be seen that we employ a 40 preferably cylindrical body bar 10 bent near one end thereof to define a laterally directed substantially semi-circular bow 11 and integrally formed on or otherwise fixed upon the bar at its adjacent terminal is a socket 12. At its opposite end portion the bar is flattened to produce an eye 13 and projecting from the eye in substantial alignment with the bar are spaced parallel jaws 14 having flat inner faces, the flattened end 45 portion of the bar being bifurcated beyond the eye to produce the jaws. As will be observed, the jaws, as well as the eye, lie in a plane with the bow 11 and straddling the outer end portions of the jaws is a substantially U-shaped keeper 15. The keeper 50 may be welded or otherwise secured to the jaws so that the keeper will thus rigidly brace the jaws against spreading.

In Figure 1 of the drawings, we have shown the manner in which our improved wrench is used for tightening the nuts of the teeth of a threshing machine cylinder. The cylinder is indicated at 16 and the cylinder shaft at 17. As is customary, the cylinder is formed of a plurality of longitudinal bars and mounted on said bars are the cylinder teeth, one of which is conventionally illustrated at 18. At its base, the tooth is provided with a reduced stud 19 extending through the adjacent bar of the cylinder and threaded on said stud is a nut 20 at the inner side of the bar securing the tooth in position. As illustrated, the body bar 10 of the wrench is inserted in the cylinder between adjacent bars thereof opposite the tooth 18 and the socket 12 engaged with the nut 20, the bow 11 being so positioned with respect to said socket that said bow will be disposed at the plane of the cylinder shaft 17. Accordingly, a bar or other lever may, as suggested in dotted lines in Figure 2, then be engaged through the eye 13 of the wrench, when said bar or lever may be operated for turning the wrench and tightening the nut, and since the eye lies in a plane with the bow the position of the bow with respect to the shaft 17 may be easily determined by observing the disposition of the eye. The nuts of all of the cylinder teeth may, of course, be tightened in like manner so that the tool will, in practical use, thus be found highly convenient as well as efficient. The jaws 14 are provided in order that the tool may be employed for straightening cylinder teeth. To accomplish this operation the jaws are, as shown in Figure 3, engaged with the tooth to be straightened, a tooth being conventionally illustrated at 21, when the body bar 10 of the wrench may be used as a lever for bending the tooth. As will be observed, the jaws are spaced apart to snugly accommodate the tooth therebetween while, as particularly brought out in Figure 4, the keeper 15 will abut an edge of the tooth for limiting the jaws against displacement therefrom. At the same time, the keeper will act to brace the jaws against the strain thereon during the bending operation. Accordingly, the tool may be manip- 55

ulated for straightening the tooth without fear of snapping off the jaws or dislocating the jaws from engagement with the tooth.

- 5 Having thus described the invention, what is claimed as new is:

In a cylinder tooth wrench, a body bar bifurcated at one end to define spaced tooth engaging jaws, and a substantially U-shaped

keeper straddling the free ends of the jaws to extend therebetween at corresponding side edges of the jaws bracing the jaws against spreading.

In testimony whereof we affix our signatures.

LOUIS J. STOLL. [L. S.]
ERNEST JOHNSON. [L. S.]
